BATTERY POWERED SHOE BRUSH

Alvin Polatchek, New York, N.Y., assignor to Shields, Inc., Attleboro, Mass., a corporation of Massachusetts

Filed Feb. 1, 1966, Ser. No. 822

Term of patent 14 years

(Cl. D9—2)

FIG. 1.

FIG. 2.

FIG. 3.

FIG. 4.

FIG. 5.

FIG. 6.

FIG. 1 is a top plan view of a battery powered shoe brush embodying the present invention;

FIG. 2 is a side elevation thereof looking from the bottom of FIG. 1;

FIG. 3 is an elevational view taken from the opposite side from FIG. 2;

FIG. 4 is a front elevational view thereof;

FIG. 5 is a rear elevational view thereof; and

FIG. 6 is a bottom plan view thereof.

The dominant features of my design reside in the portions shown in full lines.

I claim:

The ornamental design for a battery powered shoe brush, as shown and described.
